BED RAIL FASTENER

John I. Norris, East Grand Rapids, Mich.

Application July 13, 1931. Serial No. 550,418

2 Claims. (Cl. 5—298)

This invention relates generally to bed constructions and more particularly to a side rail construction therefor.

As is well understood by those skilled in this art, this rail connects the head to the foot of the bed in a rigid relationship and hence combines the several parts into a rigid structure. However, in previous constructions the bed rail has consisted merely of a single member which member serves to transmit both tensile and compressive forces. This construction has a disadvantage in that the connections between the head of the bed and the bed or side rail and likewise the connection at the foot of the bed must be extremely rigid and yet be capable of disassembly.

It is one of the principal aims or objects of this present invention to create or construct a bed rail construction which may be quickly fastened to the head and the foot of the bed in an extremely rigid manner thereby giving a bed frame which will not sway or be distorted by any weight or force thereon.

Another object of my invention is to provide means whereby the several connections may be easily and expediently tightened whenever such is necessary, thus giving a properly aligned article of furniture during its entire life.

Still another object of my invention resides in my novel means for maintaining the slats at exactly right angles to the bed or side rail. Thus the slats are not only held in their proper positions whereby they properly support the springs thereon, but they also tend to reinforce the combined bed spring during its use.

Still another feature of my invention resides in the novel tightening means which consists of a lock nut having a bail-like handle whereby it is always ready for instant adjustment.

Briefly described, my invention consists of a bed rail having a longitudinal recess therein for the reception of a tension rod, this rod having a hook at one end, this hook being fastened to the foot of the bed, and an adjustable connection at its other end, this connection being fastened to the head of the bed whereby the head of the bed may be drawn toward the foot thereof. The bed rail proper is held in abutting relationship by means of dowels between the head and the foot of the bed and the rod member tightly clamps the bed rail therebetween.

Further objects, and objects pertaining to the details and economies of construction and operation of my invention will definitely appear from the detailed description to follow.

55 In the drawing:

Fig. 1 is a view looking from the inside of the bed frame, parts of the foot posts being broken away in order to illustrate the connection between the tension rod and said foot post.

Fig. 2 is a view of the head post, this view being taken in the direction illustrated by the arrow A in Fig. 1.

Fig. 3 is a view in cross section taken along the line 3—3 of Fig. 1.

Fig. 4 also illustrates the construction of the head post, this view being taken along the line 4—4 of Fig. 2.

Fig. 5 is a view in cross section taken along the line 5—5 of Fig. 1.

Similar numerals refer to similar parts throughout the several views.

Referring particularly to Fig. 1, 10 designates the head post of a bed of any desired type and 11 the foot post associated therewith. A bed rail 12 is recessed on its inner face as indicated at 13, 75 this recess terminating in a groove 14 as clearly shown in Fig. 5. The bed rail 12 is of rectangular construction, see Fig. 5, and has dowels extending therefrom at either end thereof. These dowels are designated by the numeral 15 and are indicated in dotted lines in Fig. 5. As clearly shown in Fig. 1 the dowels 15 extend into the respective head and foot posts and maintain the bed rail against movement in a vertical direction.

A round tension rod 20 is provided with a hook portion 21 and this rod seats in the groove 14 in the bed rail 12. The hook 21 extends around a round pin 22, which is rigid with the foot post 11 and thus a universal connection is had therebetween thus permitting a perfect fitting connection between the bed rail 12 and the foot post 11. The pin 22 extends through a recessed portion in the foot post, as clearly shown in Fig. 1.

The other end of the tension rod 20 extends through the head posts 10 and is threaded as indicated at 23. A cylindrical cup-shaped nut 24 engages with the threaded portion 23 of the rod 20 and revolubly seats in a recess 25 in the head post.

The nut 24 has a depending bail 26 pivotally connected thereto as clearly shown in Fig. 2 and this handle or bail member serves as a means to operate or rotate the nut 24 thus advancing the same along the threaded portion of the rod 20 105 and placing the bed rail proper under compressive stress. The rod 20 is placed under tension as will be readily understood.

The locking nut 24 is grooved as indicated at 28 and nails 29 are so driven into the head posts 110

as to extend into the grooves 28 and thus prevent withdrawal of the nut 24.

Referring now to Figs. 1 and 5, 30 designates wooden blocks which are fastened in spaced relationship in the grooves 13 of the bed rail 12. These blocks 30 are so spaced as to permit the ends of the slats (not shown) to be placed therein and after the slats are once in position they cannot be removed by any accidental movement or tipping of the bed proper.

The utility of my invention will be readily perceived. The tension rod holds the head of the bed tightly toward the foot thereof upon the tightening of the nut 24 and the bed rail resists movement by being placed under compression and hence an extremely rigid and durable bed construction will be had. Should the several members become loose or wobbly at any time it is only necessary to grasp the bail or handle 26 and rotate the nut 24 so that the rod 20 will be placed under the proper tension.

As will be appreciated, my invention is applicable for use in many locations, one, for example, being table constructions wherein the legs may be efficiently held and braced by my novel tensioning and reinforcing device.

Having thus described my invention I desire it to be understood that the invention is in nowise limited to the particular illustrative embodiment disclosed, the scope thereof being set forth in the following claims.

I claim:

1. In combination, a foot post, a head post, a rod connected with said foot post, said rod extending through the head post, means associated with the head post end of the rod to draw the head post toward the foot post, a bed rail, having a groove therein to receive said rod, located between the head post and the foot post to prevent movement of these two members toward each other, said groove being enlarged at its top portion and blocks slidably mounted in said enlarged portion, said rod being received in said groove near the bottom thereof.

2. In a bed construction of the class described, a foot post, a head post, a rod connected with the foot post and extending through said head post, the free end of the rod being threaded, nut means threaded onto the rod whereby rotation of said nut pushes the head post toward the foot post, compression means between the head post and the foot post, dowels between the compression means and the foot and head posts respectively, said compression means having a groove extending entirely along its length to receive said rod and additional means to close said groove, said additional means holding the rod in engaged position in the said groove.

JOHN I. NORRIS.
